(57) **CLAIM**

The ornamental design for a combined shedding blade and slicker brush, as shown and described.

DESCRIPTION

FIG. 1 is a perspective view showing the ornamental design of my new combined shedding blade and slicker brush;

FIG. 2 is a front view of the combined shedding blade and slicker brush, the bristles of the brush being shown in phantom; and

FIG. 3 is a side view of the combined shedding blade and slicker brush, the opposite side view being a mirror image thereof;

FIG. 4 is a rear view of the combined shedding blade and slicker brush;

FIG. 5 is a top plan view of the combined shedding blade and slicker brush; and,

FIG. 6 is a bottom view of the combined shedding blade and slicker brush.

The portions shown in broken line are for illustrative purposes only and form no part of the claimed design.
